UNITED STATES PATENT OFFICE

2,182,003

REFRIGERATOR

Henry H. Roark, Sac City, Iowa

Application April 11, 1938, Serial No. 201,343

1 Claim. (Cl. 211—146)

The principal object of this invention is to provide a refrigerator construction that is handy and durable in use, economical in manufacture and refined in appearance.

More specifically the object of this invention is to provide a cylindrical refrigerator having holding and supporting trays that are rotatable and that are vertically adjustable.

These and other objects will be apparent to those skilled in the art.

My invention consists in the construction arrangement and combination of the various parts of the device, whereby the objects contemplated are attained as hereinafter more fully set forth, pointed out in my claim and illustrated in the accompanying drawings, in which:

Fig. 1 is a front view of my refrigerator with sections cut away to more fully illustrate its construction.

Fig. 2 is an enlarged top plan view of one of the rotatable trays.

Fig. 3 is an enlarged side sectional view of a portion of one of the trays and its associate mechanisms.

Fig. 4 is an enlarged side sectional view of the means for adjustably and rotatably supporting a tray.

Fig. 5 is an enlarged top plan view of the vertical adjustable bearing element.

Fig. 6 is an enlarged cross sectional view of the release mechanism taken on line 6—6 of Fig. 4.

Although refrigerators are universally used, they are not handy in use. The reason for this is that they are generally of rectangular construction and when the door is opened the supporting shelves or trays are positioned wholly inside the storage compartment. Also it is most difficult to obtain articles that are located on the shelves at the extreme inside back of the storage compartment. I have overcome such objections as will hereinafter be appreciated.

Referring to the drawings, I have used the numeral 10 to designate the housing of my refrigerator. This housing may be of any suitable material and construction. If desired this housing may be rectangular but I recommend that it be cylindrical as shown in Fig. 1, the advantages of which will hereinafter be pointed out. The numeral 11 designates a door hingedly secured to the refrigerator housing 10. My refrigerator may be of the electric or gas type or may be of the ice cake type. The numeral 12 designates a vertical shaft centrally mounted inside the storage compartment of the refrigerator and directly back of the door 11. This shaft is a

threaded one as shown in Fig. 4. Threaded onto this shaft 12 is a plurality of bearing elements 13. In the drawings I show two of these bearing elements, but any number may be used according to the number of supporting trays desired. Obviously by rotating these bearing elements 13 to the right or left, they will be accordingly lowered or raised in their relative positions on the shafts 12. The numeral 14 designates a vertical longitudinal groove at the side of the shaft post 12. The numeral 15 designates a lug integrally formed on the side of each of the bearing elements 13. The numeral 16 designates a well extending into each of the portions 15 and 13 as shown in Fig. 4. The numeral 17 designates a rod slidably mounted extending through each of the bearing elements 13, and one of the wells 16. Embracing each of these shafts 17 is a cup 18 threaded onto the outer end of the projection 15 through which the rod 17 rotatably and slidably operates. The numeral 19 designates projections on each of the cup cap members 18 and extending into a well 16. The numeral 20 designates a washer rigidly secured on each of the rods 17 and inside the well in which the rod operates. The numeral 21 designates a coil spring embracing each of the rods 17 having its forward end engaging the washer 20 and its rear end engaging the projection 19 as shown in Fig. 4. By this construction the coil spring 21 will yieldingly hold the forward end of the rod 17 and the channel groove 14 of the shaft 12. Obviously when the rod 17 of the bearing member 13 so engages the channel groove 14, the bearing member 13 will be prevented from relative rotation on the shaft 12. The numeral 22 designates a bayonet slot in the outer end of each of the lug projections 15. Each of these bayonet slots extends first rearwardly and then downwardly as shown in Fig. 3 and communicates with the rod 17 by virtue of a cut away portion on the projection 19. After the rod 17 and cap 18 have been assembled a pin 23 is inserted in the bayonet slot and driven into a receiving hole in the rod 17 as shown in Fig. 4. The numeral 24 designates a knurled knob handle rigidly secured on the outer end of each of the rods 17. Obviously when it is desired to rotate a bearing member 13 for a vertical adjustment purpose, the knob 24 is pulled outwardly and rotated to bring the pin 23 into the lowered position of the bayonet slot 22. This section brings the forward end of the rod 17 out of engagement with the groove in the shaft 12 and holds the rod 17 in such inoperative position. With the rod 55

in this position, the bearing member 13 may be rotated to the left or to the right to change its vertical position on the shaft 12. When the bearing member 13 reaches the desired location, 5 the knob 24 is rotated to the right to bring the pin 23 out of engagement with the vertical portion of the bayonet slot 22 and into the horizontal slot portion of the bayonet slot. When the pin 23 is in such a position the coil 10 spring 21 by exerting pressure on the washer 20 will move the rod 17 forwardly to engage the channel groove 14. The channel groove 14 is positioned on the forward side of the shaft 12 as shown in Fig. 1 in order that the knurled knobs 15 24 may be directly in front of the user when the refrigerator door is opened. The numeral 25 designates a bearing sleeve rotatably and slidably mounted on the shaft 12 and above each of the bearing elements 13. These sleeves 25 are 20 not threaded on the shaft 12. The numeral 26 designates a circular tray plate or shelf rigidly secured to each of the sleeve bearings 25. The numeral 27 designates an upwardly extending flange on the periphery of each of the members 25. Obviously as each of the members 25 rotatably rests on the top of the bearing member 13, the tray plates 26 may be easily manually rotated on the shafts 12. Their height position within the refrigerator housing may be lowered or raised 25 by adjusting the positions of the members 13 as herebefore explained. To facilitate the manual rotation of the shelves 26, the ball race 28 may be placed between each of the bearing members 13 and collars 25 as shown in Fig. 4. 30 35 From the foregoing it will readily be seen that I have provided a refrigerator construction that is very handy in use. When it is desired to

obtain some object in the inside rear of the refrigerator, it is merely necessary to rotate the shelf or tray 26 to bring the desired object to the front portion of the refrigerator. By making the housing of the refrigerator cylindrical, it 5 will be noted that when the door is opened the circular shelf tray 26 will extend outwardly and beyond the plane of the opening of the refrigerator.

Some changes may be made in the construction 10 and arrangement of my improved refrigerator without departing from the real spirit and purpose of my invention, and it is my intention to cover by my claims any modified forms of structure or use of mechanical equivalents which may 15 be reasonably included within their scope.

I claim:

In a device of the class described, a housing, a vertical threaded shaft inside said housing, a bearing member threaded on said shaft, a 20 longitudinal groove in said threaded shaft, a rod slidably mounted in said bearing member capable of engaging said channel groove at times, a means for yieldingly holding said rod towards said shaft for preventing the rotation of said 25 bearing element relative to said threaded shaft at times, a projection on said bearing element surrounding said rod and having a bayonet slot cut therein, a pin on said rod capable of engaging said bayonet slot in said projection when said 30 rod is manually pulled rearwardly out of engagement with said groove in said threaded shaft, and a supporting tray element rotatably mounted on said shaft and operatively supported by said bearing member. 35

HENRY H. ROARK.
